ALTERNATING ROTARY GEARING FOR WASHING-MACHINES.

1,149,283.

Specification of Letters Patent. Patented Aug. 10, 1915.

Application filed December 27, 1911. Serial No. 668,185.

To all whom it may concern:

Be it known that I, OTTO G. PFEIFFER, a citizen of the United States, and residing at Salt Lake City, in the county of Salt Lake and State of Utah, have invented certain new and useful Improvements in Alternating Rotary Gearing for Washing-Machines, of which the following is a specification.

10 This invention relates to driving gearing, and more particularly to driving gearing for washing machines.

This invention as to some of its features is an improvement on my Patent No. 15 981,940, granted Jan. 17, 1911.

A driving gearing for washing machines must possess certain characteristics which especially adapt it for driving the rotary member of such a machine. The rotary member generally consists of a drum, which is partially filled with clothes to be washed, and which runs in a casing containing water. This member must have its direction reversed at intervals, so as not to wind up 25 the clothes in lumps as would be caused by continuous motion in one direction. In view of the fact however that the member to be reversed has considerable weight especially when filled with clothes, difficulty 30 has been experienced in constructing a gearing which will drive the rotary member of a washing machine alternately in reverse directions without causing excessive shocks or jars at the points of reversal.

35 One of the objects of this invention therefore is to construct a gearing which is arranged to drive a heavy driven member alternately in reverse directions without shocks or jars at the point of reversal; which 40 can be readily thrown into and out of operation whether the prime mover or motor is in motion or stationary; which will be simple in its construction, positive in its operation, and easily manipulated.

45 Another object is to combine with the alternating rotary gearing a wringer driving gearing which is arranged to drive the wringer shaft at will in either direction, and which wringer driving gearing is operated 50 from and has its operating elements mounted on the same shaft as the alternating rotary gearing.

Further objects will appear from the detail description taken in connection with the accompanying drawings in which:

55 Figure 1 is a section on the line 1—1 Fig. 2, Fig. 2 is a section on the line 2—2 Fig. 1, and Fig. 3 is a detail of a part of the controlling means for the reversing gearing.

Referring to the accompanying drawings, 60 10 designates a washing machine casing and 11 a drum arranged to rotate therein in reverse directions and arranged to receive clothes to be washed. The washing machine construction is fully shown and described 65 in my application Serial No. 668,184 filed of even date herewith.

The casing body is supported in a pair of end frames, one of which is shown at 12. These end frames are preferably malleable 70 castings while the casing body is of sheet metal. The end frame 12 has secured thereto or cast integral therewith a series of bearing lugs 13, 14 and 15, the lugs 13 and 14 forming bearings for a main drive shaft 75 17 hereinafter referred to. A bracket 16 is bolted to the lugs 13, 14 and 15 and forms caps for the bearing lugs 13 and 14. A main drive shaft 17 is mounted in the bearing lugs 13 and 14 and has mounted thereon a 80 gear 18 meshing with a pinion on a motor shaft (not shown). A driven or drum shaft 19 is supported for rotation in bearings on the end frame 12 and on the bracket 16 and has a connection with the drum 10 as fully 85 described in the application referred to.

A pair of bevel gears 20 are loosely mounted on the driven shaft 19 and are arranged to be alternately clutched to the driven shaft by clutch mechanism now to 90 be described. The clutch mechanism is in this case of the expanding band type, and since the clutches for the two bevel gears are duplicate, a detail description of one will be sufficient. The bevel gear is provided 95 with a machined friction surface 21 arranged to be engaged by cooperating clutch shoes 22. A clutch shoe carrier having arms 23 is keyed to the shaft 19, and each of the clutch shoes 22 is provided with a lug 24 100 having a pin and slot connection with the arm 23 as shown at 25 so that the clutch shoes are supported near their centers for free movement toward and from the fric-

tion surface 21. Each one of the clutch shoes 22 is provided at one of its free ends with a lug 26 having an adjusting screw 27. The other ends of the clutch shoes are provided with lugs 28 pivotally supporting arms 29 having toes 30 arranged to bear against the ends of the screws 26. The ends 31 of the arms 29 are arranged to be engaged by a cone 32 slidably mounted upon the shaft 19 and arranged to be moved by means of mechanism hereafter to be described. This clutch is fully described in my copending application Serial No. 661,384, filed Nov. 20, 1911.

15 The driving shaft 17 has loosely mounted thereon a sleeve 33 mounted in the bearing lug 14 and having formed thereon a bevel gear 34 meshing with the bevel gears 20 on the driven shaft. The sleeve has also 20 formed thereon a worm 35 meshing with a worm wheel 36 mounted on a shaft 37 in bearing lugs 38 on the frame 12 and the bracket 16. A cam block 39 is formed integral with the worm wheel 36 and is provided with a cam groove 40 engaged by a cam roll 41 on one end of a lever 42 pivoted intermediate its ends on a lug 43 formed on the bracket 16. The other end of the lever 42 is provided with a fork 44 connect- 30 ed to the cone 32.

The sleeve 33 is connected with and disconnected from the drive shaft 17 by means of a jaw clutch comprising a clutch member 45 splined on the shaft and having teeth 35 thereon engaging coöperating teeth on the left hand end of the sleeve. This clutch member is operated by a fork 46 slidably mounted upon a shaft or rod 47 mounted to slide in bearing lugs 48 extending from the bracket 16. This rod has rigidly mounted thereon two collars 49 and 50 respectively, and a spring 51 is mounted on the rod between the collar 50 and the fork 46. A collar 52 is adjustably secured to the rod 47 45 and is provided with a laterally extending pin 53 engaging a slot in an actuating lever 54 pivoted upon the end frame 12. This actuating lever is arranged to throw the jaw clutch into and out of operation. In order 50 to hold the clutch in either of its adjusted positions, a lug 55 is secured to a bracket on the end frame 12 and forms stop shoulders 56 and 57 arranged to be engaged by the lever 54. The lever is shown in position to 55 hold the clutch engaged. In order to throw out the clutch, the lever is moved to the left. In order to do this it is first necessary to disengage the lever from the stop shoulder 56, and for this purpose the lever is moved 60 toward the observer, the lever itself being sufficiently elastic to permit this and also spring back behind the shoulder 57 when the clutch is disengaged.

The operation of the alternating rotary

gearing is as follows: When the jaw clutch 65 is engaged to clutch the sleeve 33 to the drive shaft, the bevel gears 20 will be rotated in opposite directions. As the sleeve 33 rotates the worm and wheel will operate to cause the cam on the wheel to slide the 70 cone on the driven shaft 19. The clutches on the driven shaft will thus be operated to alternately connect the bevel gears with the driven or drum shaft. The worm and wheel and the cam are so designed that the drum 75 will be rotated through several revolutions and then reversed to be driven for several revolutions in the opposite direction. This mechanism therefore forms automatic mechanism for controlling the gearing so as to 80 cause the driving shaft to automatically and reversely drive the driven shaft. The construction of the controlling mechanism and its positive action causes a positive operation of the clutches, and since these clutches 85 are of the friction type and arranged to engage gradually, as fully described in application Serial No. 661,384 referred to, the operation of the gearing as a whole will be positive and without shock, as the power is 90 gradually applied to the driving shaft at the point of reversal. The jaw clutch can be engaged irrespective of the relative positions 95 of the clutch jaws on the sleeve 33 and on the clutch member 45. Thus if the clutch is 100 thrown in while the shaft 17 is stationary, and while the jaws are opposite one another, the actuation of the lever 54 will bring the jaws in engagement and compress the spring 51, permitting however the movement of the 105 actuating lever to its limit and behind the stop shoulder 56. As soon as the shaft 17 starts to rotate (as by starting the motor) the jaws will automatically snap into engagement when the recesses of one clutch sleeve coincide with the jaws of the other clutch sleeve.

The wringer is generally designated by 60, and 61 designates the wringer shaft. This shaft has mounted thereon a bevel gear 62 meshing with a bevel gear 63 on a cross shaft 64 mounted in bearing lugs 65 and 66 on the end frame 12. A bevel gear 67 is mounted on the lower end of the shaft 64 and meshes with two bevel gears 68 loosely 115 mounted upon the drive shaft 17. A jaw clutch member or sleeve 69 is splined upon the drive shaft 17 and is provided with jaws arranged to engage with coöperating jaws upon the bevel gears 68. A clutch fork 70 is 120 loosely mounted upon a shaft or rod 71 slidably mounted in bearings in the lugs 13 and 14. This rod has rigidly mounted thereon two collars 72 and 73 respectively, and springs 74 and 75 are mounted upon this rod, one between the collar 72 and the fork, and the other between the collar 73 and the fork. A vertical shaft 76 having an operating

handle 77 is mounted for rotation in bearing lugs 78 and 79 formed on the end frame 12. A disk 80 is mounted upon and connected to the lower end of the shaft 76 and is provided with a crank pin 81 connected by a pitman or link 82 with the collar 72. The disk is provided with a series of recesses 83 adapted to be engaged by a spring latch 84 mounted upon the end frame 12.

10 The connection of the drive shaft with one or the other of the gears 68 will cause the drive shaft to rotate the wringer shaft in one or another direction. The controlling means, described above, for causing such a 15 connection of the gears, is so constructed that the wringer shaft may be driven in one or another direction at the will of the operator. In the drawings, the mechanism is shown in neutral position at which time 20 both gears 68 are loose on the shaft. If the handle 77 and the shaft 76 are now rotated through a quarter of a revolution in one direction the wringer shaft will be driven in one direction, while if the handle 25 and the shaft are turned from neutral position in the opposite direction, the direction of rotation of the wringer shaft will be reversed. It will be noted that the controlling mechanism has two neutral positions, 30 namely one in which the crank pin 81 is in the position shown in Fig. 2, and another position in which the crank pin will be diametrically opposite. The shaft 76 can however be turned from either neutral position in the 35 desired direction to cause the wringer shaft to be driven in the desired direction. It will also be noted that when the shaft is in either of its clutch engaging positions, the clutch can be thrown to neutral position by turning 40 the shaft in either direction. This construction is of great advantage in washing machines, which are operated by unskilled operators, and in which the operator is liable to become excited (when the clothes are 45 tangled or caught) and forget in which way the handle should be turned to throw out the wringer shaft. With this construction however the operator is not required to remember this, since the shaft handle can be moved 50 in either direction to neutral position. The latch 84 will hold the shaft in any of its adjusted positions.

The handle 77 can be moved to its limit to throw in the clutch irrespective of the position of the clutch member. This is due to the fact that the connection between the handle and the clutch member 69 is a yielding one (through the springs 74 and 75). Thus if the handle 77 is operated to throw 55 the clutch member 69 in while the shaft 17 is stationary and while the jaws of the clutch member are opposite the co-operating jaws on the bevel gears, the clutch member 69 will be moved until the jaws thereon en-

gage the jaws on the bevel gear and further movement of the handle will serve to compress one of the springs 74 or 75. As soon as the shaft 17 starts to revolve, or revolve sufficiently to align the jaws on the clutch member with the recesses on the bevel gear, 70 the parts will snap together under the action of the compressed spring.

The automatically controlled driving mechanism for the washing machine drum and the manually controlled driving mechanism for the wringer have their driving elements mounted upon the same driving shaft so that the parts will constitute together a condensed structure. In washing machines while the drum is operating the 75 wringer will generally be stationary and vice versa. In view of this fact the gear 18 and the shaft need only be designed of a strength sufficient to operate one of these driven members.

80 It is obvious that various changes may be made in the details of construction without departing from this invention, and it is therefore to be understood that this invention is not to be limited to the specific construction shown and described.

Having thus described the invention what is claimed is:

1. In a machine of the class described, the combination with a drive shaft and a driven shaft, of a bevel gear on said drive shaft, a pair of bevel gears on said driven shaft, a sleeve loosely mounted on said drive shaft and connected with said first bevel gear, mechanism, including a member connected 95 with said sleeve, for clutching said second bevel gears alternately to said driven shaft, to cause said drive shaft to automatically drive said driven shaft in reverse directions, and means for connecting and disconnecting 100 said sleeve to and from said drive shaft, whereby the operation of said driven shaft may be controlled without affecting the operation of said drive shaft.

2. In a machine of the class described, the combination with a drive shaft and a driven shaft, of a bevel gear on said drive shaft, a pair of bevel gears on said driven shaft, a sleeve loosely mounted on said drive shaft and having said first bevel gear integral 115 therewith, mechanism, including a worm integral with said sleeve, for clutching said second bevel gears alternately with said driven shaft, constructed to cause said drive shaft to automatically drive said driven shaft in reverse directions, and means for connecting and disconnecting said sleeve to and from said drive shaft, whereby the operation of said driven shaft may be controlled 120 without affecting the operation of said drive shaft.

3. In a machine of the class described, the combination with a drive shaft and a driven

shaft, of a bevel gear loosely mounted on said drive shaft, a pair of bevel gears on the driven shaft meshing with said first bevel gear, mechanism, including a member 5 loosely mounted on said drive shaft and connected with said first gear for controlling said gears, constructed to cause said drive shaft to automatically drive said driven shaft in reverse directions, and a clutch on 10 said drive shaft positioned between the bevel

gears on the driven shaft and constructed to connect and disconnect said first bevel gear to and from said drive shaft.

In testimony whereof I affix my signature in presence of two witnesses.

OTTO G. PFEIFFER.
